PLUMBING FIXTURE

Theodore Mikolajczak and Steven Partyka,
Hammond, Ind.

Application December 22, 1938, Serial No. 247,140

9 Claims. (Cl. 4—252)

This invention relates to an improved plumbing fixture which in the preferred embodiment of the invention is constructed of cast-iron or other suitable material. The improved fixture of this invention is adapted to be interposed between a toilet bowl and soil pipe and also to provide a protective apron and drain board extending under the tank portion of a conventional toilet. The visible surface of the device is preferably finished by enameling or other suitable treatment.

One of the principal objects of the improved fixture of this invention resides in the provision of means for providing an economical and efficient device to prevent rotting away of floors and other structures upon which a toilet bowl is conventionally fastened.

Another important object of advantage resides in the provision of means for conveying leakage or waste from the surface of the improved device into the soil pipe.

Still another and further object of importance resides in the provision of means for preventing gas and odors from the soil pipe from escaping through the improved fixture.

An additional object of importance and advantage resides in the provision of means for securing a toilet bowl and soil pipe to the improved fixture.

Additional objects of advantage and importance will become apparent as the following detailed description progresses, reference being had to the accompanying drawing, wherein

Fig. 1 is a top plan view of a plumbing fixture which embodies the invention.

Fig. 2 is a longitudinal section taken on line 2—2 of Fig. 1.

Fig. 3 is a slightly enlarged transverse section of the device taken on line 3—3 of Fig. 1.

Fig. 4 is a longitudinal section taken on line 4—4 of Fig. 1.

As shown in the drawing:

The reference numeral 10 indicates generally the body of the improved plumbing fixture of this invention. The fixture is preferably substantially T-shaped in plan formation. This particular shape of the device provides a drain board having a perimeter extending slightly beyond the outermost edges of a conventional toilet bowl and flush tank assembly.

One edge 12 of the device is substantially straight. This edge is adapted to be positioned against a wall. The other edges of the improved fixture are flanged as is indicated by the reference numeral 14. The bottom of the flanged edge

14 provides supporting portions for the fixture. The upper surfaces of the flanges 14 provide supporting means for floor boards, tile, or the like.

Closely adjacent the edges thereof is a groove 16. The groove 16 extends around three sides of the longitudinal portion of the device parallel to the edges thereof. The groove 16 is depressed in the central portion of the fixture, as is best shown in Fig. 4.

Formed in the depressed portions of the groove 16 is an outlet passageway 18. The outlet passageway 18 opens into a substantially U-shaped trap 20. The trap 20 empties into the soil pipe 22 through the passageway 24. It is to be noted that the passageway 24 extends through the conventional packing 26 which is interposed between the interior surface of the soil pipe receiving aperture and the exterior surface of the soil pipe. The soil pipe 22 is notched or pierced as is indicated by the reference numeral 28 and best shown in Fig. 3.

The entire central surface 30 of the longitudinal portion of the improved fixture is substantially level, as is best shown in Figs. 1 and 2. This level surface is adapted to have a toilet bowl 25 positioned thereon.

Formed in the central portion of the fixture on opposed sides of the soil pipe receiving aperture are screw threaded anchor bolt receiving holes 32. The holes 32 are adapted to co-act 30 with anchor bolts in securing a toilet bowl to the fixture and the soil pipe 22. Auxiliary anchor bolt securing means 34 are provided for securing the front end of a toilet bowl to the fixture.

Suitable reinforcing ribs 36 are provided to 35 prevent warping or misalignment of the fixture.

It will be apparent from the foregoing that herein is provided an efficient fixture which in addition to enhancing the appearance of a toilet assembly also provides a means for conveying leakage from the flush bowl or any of the joints of the toilet assembly into the grooves 16 and thence through the passageway 18 into the trap 20 and thence through the passageway 24 into the soil pipe 22. Consequently, leakage or dampness from the toilet assembly is not permitted to contact the floor or floor supporting structures. Accordingly, deterioration and rotting away of such structures because of continued dampness from leakage is entirely eliminated.

It will also be apparent from the foregoing that herein is provided an improved fixture which may be employed with any conventional floor supported toilet assembly.

It will be apparent to those skilled in the art 55

to which the device appertains that numerous changes and alterations in construction and design may be made all without departing from the spirit or scope of this invention. Accordingly, it is understood that the patent granted hereon is not to be limited to the preferred embodiment here disclosed nor in any other manner except as necessitated by the terminology of the appended claims when given the range of equivalents to which they may be entitled.

10 We claim as our invention:

- 15 1. In a plumbing fixture comprising a substantially flat T-shaped member having a soil pipe receiving aperture in the central portion thereof, a horizontal flange extending outwardly from the body of said T-shaped member, a groove closely adjacent each edge of said longitudinal portion, and an anchor receiving bolt hole intermediate said aperture and each groove.
- 20 2. In a plumbing fixture comprising a substantially flat T-shaped member having a soil pipe receiving aperture in the central portion thereof, floor supporting means formed of the edges of said T-shaped member, a groove closely adjacent each edge of said longitudinal portion, said grooves diminishing in depth toward each end of said member, and an anchor receiving bolt hole intermediate said aperture and each groove.
- 25 3. In a plumbing fixture comprising a substantially flat T-shaped member having a soil pipe receiving aperture in the central portion thereof, means on the edge of said T-shaped member for engaging the bottom surface of flooring members in abutment with said T-shaped member, a groove closely adjacent each edge of said longitudinal portion, said grooves diminishing in depth toward each end of said member, a drain passageway extending from the deepest portion of each groove to said soil pipe receiving aperture, and an anchor receiving bolt hole intermediate said aperture and each groove.
- 30 4. In a plumbing fixture, a relatively flat member having a soil pipe receiving aperture in the central portion thereof, passageways extending from a point closely adjacent the opposed edges of said fixture into said aperture, continuing passageways connected to said first named passageways and extending into a soil pipe positioned in said aperture, and means whereby a toilet bowl may be secured to said fixture.
- 35 5. In a plumbing fixture, a relatively flat member having a soil pipe receiving aperture in the central portion thereof, passageways extending from a point closely adjacent the opposed edges of said fixture into said aperture, pipe means for

extending said passageway into a soil pipe positioned in said aperture, flange means on the edge of said fixture for engaging the bottom surface of floor members in abutment therewith, means intermediate the ends of said passageways preventing the return of gases, and means whereby a toilet bowl may be secured to said fixture.

6. In a plumbing fixture a relatively flat member having a soil pipe receiving aperture in the central portion thereof, passageways extending from a point closely adjacent the opposed edges of said fixture into a soil pipe positioned in said aperture, means intermediate the ends of said passageways preventing the return of gases, means whereby a soil pipe may be secured in said aperture, a floor supporting flange formed on three of the four edges of said fixture, and means whereby a toilet bowl may be secured to said fixture.

7. In a plumbing fixture, a relatively flat member having a soil pipe receiving aperture in the central portion thereof, passageways extending from a point closely adjacent the opposed edges of said fixture into said aperture, means intermediate the ends of said passageways preventing the return of gases, means whereby a soil pipe may be secured in said aperture, said means comprising a packing receiving recess in the upper portion of said aperture, and means whereby a toilet bowl may be secured to said fixture.

8. In a plumbing fixture, a relatively flat member having a soil pipe receiving aperture in the central portion thereof, passageways extending from a point closely adjacent the opposed edges of said fixture into said aperture, means intermediate the ends of said passageways preventing the return of gases, means whereby a soil pipe may be secured in said aperture, said means comprising a packing receiving recess in the upper portion of said aperture, a drain pipe extending from each of said passageways into said soil pipe, and means whereby a toilet bowl may be secured to said fixture.

9. In a plumbing fixture adapted to form a support and joint between a toilet bowl and a soil pipe, a soil pipe receiving aperture in the central portion of said fixture, a groove closely adjacent each longitudinal edge of said fixture, a drain passageway extending from each groove through said aperture into a soil pipe, trap means intermediate the ends of each passageway, and means for securing a toilet bowl to said fixture.
